COIN CONTROL

Application filed May 27, 1929. Serial No. 366,427.

This invention relates to improvements in coin controls and it consists of the constructions, combinations and arrangements herein described and claimed.

An object of the invention is to provide a coin control which has the facility of being applicable to any style of vending machine in which the unlocking of a plunger or its equivalent is a pre-requisite to the operation of the machine for the dispensation of an article.

Another object of the invention is to provide a coin control which will prevent the discharge of an article from the machine to 15 which said control is attached until a plurality of good coins equal in value to that of the article is inserted thereinto.

Another object of the invention is to provide a coin control in which a system of 20 gauging or proportioning levers is the dominant feature, the principle of this system being to gauge the coins and prevent the vending of an article until the aggregate value of the coins equals that of the article.

Another object of the invention is to provide a coin control in which a locking hook will be moved toward an unlocking position upon operation by a coin of any lift finger of a lever system, but which can be made to 25 assume the unlocking position only by a cumulative action of the lever system upon insertion of coins equal in value to the article sought to be bought.

Another object of the invention is to provide a unit coin control which is not only the common actuator of a plurality of discharger slides but also is easily separable from the vending machine mechanism.

Other objects and advantages will appear 40 in the following specification, reference being had to the accompanying drawings, in which:

Figure 1 is a cross section of a portion of a vending machine illustrating the embodiment of the improved coin control,

Figure 2 is a horizontal section taken substantially on the line 2—2 of Figure 1,

Figure 3 is a vertical section taken on the line 3—3 of Figure 1,

Figure 4 is a detail cross section taken sub-

stantially on the line 4—4 of Figure 2, illustrating the action of a dime upon the lever system,

Figure 5 is a similar view taken substantially on the line 5—5 of Fig. 2, illustrating 55 the action of a five cent piece upon the lever system,

Figure 6 is a detail elevation of a portion of the front cover plate and its associated parts,

Figure 7 is a detail perspective view of the lock release hereinafter referred to,

Figure 8 is a detail perspective view of the locking hook.

As brought out in one of the foregoing 65 statements of the objects of the invention, it is a purpose to provide a coin control for what might be described as universal application, that is to say, it is capable of use in any style of vending machine in which the 70 unlocking of a plunger or some equivalent part is a pre-requisite to that operation of the mechanism which will release or discharge the article sought to be purchased. In order to illustrate one adaptation of the coin control it is herein shown in conjunction with enough of the mechanism of the vending machine in a copending application for patent, filed by George E. Nicholson under date of May 27, 1929, Serial No. 366,426, otherwise 75 known as Case No. 1.

A description of the details of this particular vending machine is reserved for the companion patent application, but enough of the vending machine is described herein to 85 give the reader an understanding of the purpose of the coin control. The latter has another quality that was especially developed to meet the exigencies of modern trade. The number of articles selling at prices exceeding 90 five cents is rapidly increasing so that the purchaser is often confronted with the requirement of paying ten cents, fifteen cents, or other multiples of one dollar for commodities such as cigarettes and the like.

It is easy to see that a situation is likely to arise wherein the intending purchaser may be deprived of the convenience of an immediate purchase and the vendor of the advantage of a sale by virtue of the purchaser not 95

having coins of proper denominations. The aforesaid quality of the coin control is such that the intending purchaser may insert any available coins so long as the aggregate value is equal to the cost of the article sought, and thus be able to bring about an operation of the vending machine and complete the purchase of the article.

This principle is illustrated by using a fifteen cent value as an example. The vending machine is supposed to contain articles that will sell for fifteen cents, and agreeable with this premise the coin control is capable of operation either upon the insertion of three five cent pieces or a dime and one five cent piece. According to the extension of the principle, other combinations of coins could be used in a coin control patterned after the one herein described and in fact any combinations of coins in multiples up to one dollar might be used as will presently be understood.

It is the action of a leverage system that makes this variable use of coins possible. This leverage system is actually a compound lever, and its function is to gauge the coins so that the cumulative action of the lift fingers or proportioning levers as they might be called, will be sufficient to raise a locking hook from its locking position only when coins of a sufficient value have been inserted. A sufficient raising of the locking hook is the ultimate purpose of the coin control and it is by this raising of the locking hook that the plunger is freed for its movement to operate the vending machine.

Reference is now made to the drawings. The vending machine is first briefly described to dispose thereof and that the latter description may be concentrated upon the coin control. A hollow base 1 carries a superbase 2 upon which a framework 3 is rested and constructed so as to define a space or column 4 in which articles are supported by a discharger slide 5 which is capable of being operated by a selector finger 6. There is a series of these fingers as well as of the discharger slides because the vending machine will be equipped to handle a number of kinds of articles.

A selecting shaft 7 carries a series of lifters 8 which are equal in number to the slides 5 and fingers 6, the idea being that a turn of the shaft will move the companion finger 9 into locking engagement with the discharger slide 5 of the selected article column so that a subsequent movement of a selector plate 9 by which the series of fingers is carried will cause a displacement of the locked discharger slide from the column 4 so that the stack of articles can drop to the guide 10 along which the slide is movable. The return movement of the slide will discharge the article into a chute 11.

The subsequent movement just referred to

is brought about by pushing on the button 12 of a plunger 13. This plunger has connection with the selector plate 9 by means of lugs 14. The connection of the lugs with the plunger is fixed so that any movement of the plunger will be transferred to the selector plate, hence to the selected one of the discharger slides. It is the purpose of the coin control either to lock the plunger against movement, as when no coins are inserted or coins of an insufficient value, and to permit the movement of the plunger when the proper condition exists.

Attention is now directed to the details of the coin control. This comprises a base plate 15 which is fixed in position by virtue of being riveted or otherwise secured at 17 to an angle bracket 18 in turn secured to the front cover plate 19 of the base 1. The base 15 and plate 19 may be generally identified as a fixed mounting for a coin plate 20 and its appurtenances. It is in respect to the base and cover plates that the plunger 13 is slideable, the cover plate in fact constituting one of the bearings of the plunger. For the foregoing purpose the coin plate 20 has a pair of lugs 21 which are turned down from the plate and are attached to the plunger.

This attachment is intended to be fixed as far as the operation of the apparatus is concerned. There must be no movement of the plunger relatively to the coin plate. The coin plate must travel with the plunger, and inasmuch as the coin plate and the selector plate 9 are similarly attached to the plunger, it follows that a movement of the plunger will bring about a simultaneous movement of the coin plate and selector plate. However, to carry out one of the purposes of the invention it must be understood that the connection at 21 is not necessarily made with this particular plunger 13. It might be made with something that is equivalent to the plunger, or something that by its operation will bring about discharge of an article from a vending machine.

A locking hook 22 tends to prevent movement of the plunger 13 to an extent sufficient to fully displace the slide 5 from the column 4. For this purpose the hook occupies a lock slot 23 in the coin plate 20. The coin plate, and consequently the plunger 13, could be moved inwardly only until the front end of the slot engaged the near end of the hook 22. The shank 24 of the hook has a common pivotal mounting with a set of lift fingers 25, 26, 27 and 28 (Fig. 2) which exercise a proportioning function or gaging action upon the lever system or actuator means later described, these fingers being simultaneously adjustable by an assemblage of heterogeneous coins inserted into the receivers 29, 30, 31 and 32 that the locking hook 22 will be raised to various heights and ultimately out of the slot 23 so that the coin plate 20 and

plunger 13 may partake of unimpeded inward movement.

Ears 33 provide the mounts for a shaft 34 that constitutes the common pivot of the lift fingers and the locking hook. These ears are bent up from the base 15, and since the latter is fixed it follows that the ears and their carried parts are also fixed so far as reciprocating movement is concerned. In other words, the set of lift fingers and the locking hook are capable of limited up and down rocking motion but they do not reciprocate with the coin plate or plunger.

Spring rings 35 (Fig. 2) fitted in grooves (not shown) in the protruding ends of the shaft 34 hold the latter in place upon the ears. Sleeves 36 assembled upon the shaft 34 in alternation with the fingers 25, etc., space the latter at proper intervals and retain them in their operative positions over the receivers 29 and 30. The inner ends of the fingers are guided in slots 37 of a guide plate 38 which is fixedly secured at its ends to ears 39, similar to the ears 33, and bent up from the base 15. The lift fingers are held at the bottoms of the slot 37 largely by a spring 40 (Fig. 2) which at one end connects with and presses down upon an arm of the lock release 41 and at the other end is applied to an arm 30 of a bracket 42 upon which the lock release is pivoted.

Each lift finger has a shoulder 43 on the nether-edge (Figs. 1, 4 and 5). These shoulders are bluntly pointed, and the points either rest upon narrow webs 44 which divide the slug discharge opening 45 from coin slots 46 in the base plate 15, or are held in very close proximity to said webs by the natural engagement of the inner ends of the fingers with the bottoms of the slots 37. The openings 45 are intended for the discharge of undersize slugs into a place in the base 1 outside of the coin drawer 47. For example, the first opening 45 at the left of Fig. 2 is to discharge slugs smaller than a dime and the remaining openings 45 are to discharge slugs smaller than a five cent piece.

This brings the description to the purpose of the receivers 29 and 30. The first of these has what is called a dime hole 48, that is to say, a hole exactly the size of a new dime. A coin larger than a dime will not fit in the hole, and a slug smaller than a dime will drop through the discharge opening 45 when the plunger is pushed. The permissible unresponsive movement of the plunger, represented by the distance between the front end of the slot 28 and the near edge of the hook 22, is slightly more than sufficient to bring the slug within range of the discharge opening 45, so that should a person seek to operate the machine by placing undersize slugs in the receivers he will only be rewarded by having these dropped through the openings 45.

On the other hand, if coins of an insufficient aggregate value are inserted in the receivers 29 and 30 they will not be lost upon pushing in on the plunger 13 because the foregoing permissible movement will not advance the coin holes in the receivers sufficiently beyond the webs 44. The webs thus serve as retainers for good coins of an insufficient aggregate value. The receivers 30, 31 and 32 have five cent piece holes 49. These are exactly the size of new five cent pieces. Undersize slugs would drop through the openings 45 precisely in the manner explained in respect to the dime receiver 29.

The base plate 15 comprises the bottom of the coin holes 48 and 49. For this purpose a small portion of the plate 15 projects beyond the front cover plate 19. The projecting portion comprises a shelf, and it is upon this shelf that the only active part of the coin control, namely the receivers 29 to 32, is visible from the outside of the vending machine. The shelf is perforated at 50 at points directly under the coin holes, the idea being that the intending purchaser may be enabled to push the ball of a finger up into the perforations from the underside of the shelf in order to displace the coin or coins from the receivers should he change his mind about making the purchase or should he have inserted less than the proper number of coins.

Coins mutilated by being warped out of shape or overthick slugs will be denied admission to the machine by gauging the depth of slots 51 and 52 (Fig. 6) in the front cover plate 19 to the exact thicknesses of a dime or five cent piece as the case may be. These slots are lateral offsets of a long slot 77 (Figs. 1 and 6) in the front cover plate 19 through which the forward end of the base plate 15 protrudes. The thickness of the receivers 30, 31 and 32 will be equal to the thickness of a new five cent piece and the depth of the slots 52 will be equal to such thickness. Hence it follows that only a good five cent piece can be pushed through the front cover plate. The protruding end of the receiver 29 is ground down to the thickness of a new dime as at 53 in Figure 4. The depth of the slot 51 is equal to such thicknesses, hence it follows that only a good dime can be pushed into the machine. Should a mutilated coin be inserted the wall around the slot would obstruct its admission.

Coins stuck in the coin holes 48 and 49 either accidentally or intentionally will be dislodged by ejector tongues 54 and thus prevent repeat operations of the machine. These tongues are bent up from the base plate 15 at the inner ends of the coin slots 46 and extend into ejector slots 55 which communicate with the coin holes 48 and 49. This communication provides a necessary clear space around the shoulders 43, and were the slots 55 and holes 48, 49 divided by a web as in the

instance of the holes 45 and 46, such web would lift the fingers 25 etc., upon each initial inward movement of the coin plate 20. A full inward movement of the coin plate 20 will bring the coin in the hole 48 (for example) within range of the tongue 54, the advance of the coin under this tongue pushing the coin down and out of the hole 48, through the slot 46 and into the drawer 47.

10 The inner end of a slot 56 in the fixed base plate 15 (Fig. 1) permits the inward movement of the coin plate 20, but this extent of movement can occur only after coins of a sufficient value have been brought into play 15 to raise the locking hook 22 out of its locking position. The forward lug of the pair 21 occupies the slot 56 and upon being stopped by engagement with the inner end of the slot will prevent further inward movement 20 of the plunger 13. In moving to this engaging position the lug 21 must pass the hook 22, but the hook at such time will be in the elevated position, hence the lug can readily pass thereover.

25 The leading edge 57 of the forward lug is rounded, and the rear edge of the hook 22 is bevelled so that one can raise the other upon the return movement of the coin plate 20 and permit the latter to assume its original position. This raising movement of the hook is 30 only instantaneous, and it is immediately pressed in its original position by a spring 58 which is employed for the purpose of tending to hold the hook down. This spring 35 also exercises the function of keeping an adjustable contact screw 59 in engagement with a tongue 60 of the lock release 41. One end of the spring is applied to the shank 24 and the other to a bracket 80 which is affixed to 40 the base plate 15 and supports the center of the shaft 34 against sagging. The contact screw is carried by the shank 24 which is equipped with a lug 61 for the mounting of the screw. Although the spring 58 assists in 45 tending to hold the tongue 60 in contact with the coin plate 20 it is the particular function of the spring 40 to do that.

50 The contact of the tongue 60 with the coin plate 20 is a sliding one under conditions of idle operations of the plunger 13. In other words, should less than the requisite number of coins be inserted in the receivers and the plunger be subsequently pushed, or should the plunger be pushed without any coins having 55 been inserted, the coin plate would merely slide beneath the tongue 60 which maintains its position by virtue of the spring pressure. But should the requisite number of coins be inserted, the action of the lever 60 system would be such as to raise the tongue 65 out of contact with the coin plate, necessarily so because it is the raising of the tongue that raises the locking hook 22.

Reference is now made to the lever system 65 which comprises the actuator means for the

locking hook 22. This is composed of levers of the second order, namely levers in which the weight is suspended from a point between the fulcrum and the point of application of the power. The lift fingers 25 to 28 are levers 70 of the third order, namely levers in which the power is applied at a point between the fulcrum and the point of application of the weight. As regards the lever system which is thus especially denoted because of its particular function in respect to the lock release 75 41, the leverage of the second order is preserved throughout regardless of how many components are brought into play at one time.

An equalizer master bar 62 is pivoted at 80 63 to the lock release 41, and this pivotal connection constitutes the weight point in the operation of the coin control. One end of the bar is fulcrumed at 64 to a yoke 65 which has hangers 66 and 67 at its ends for connection of the yoke with a pair of contact levers 68 and 69. The other end of the bar 62 rests upon the dime lift finger 25, the point of contact 70 being the point of application of the lifting power to the lever system. The pivot 85 63 is exactly midway of the fulcrum 64 and power point 70 so that the pivot 63 will traverse a distance equal to one-half of that traversed by the point of contact 70 when a dime is advanced under the shoulder 43 of the 90 finger 25.

However, the leverage is multiplied as it concerns the locking hook 22, the action of the tongue 60 against the contact screw 59 being to raise the hook 22 exactly the same 100 distance as the point 70 when a dime is advanced under the shoulder 43 in the illustration already given. But the adjustment of the leverage system is such that a dime alone will not raise the locking hook 22 far enough 105 out of the lock slot 23 to give the coin plate 20 free passage beneath the hook. A dime will raise the locking hook approximately only two-thirds of the distance requisite to clear the coin plate.

110 It requires the insertion of a five cent piece into one of the remaining receivers to cause the remaining one-third lift of the hook 22. The five cent piece may be inserted into any one of the receivers because the lever action 115 of each one of the fingers 26, 27 and 28, is precisely the same on the weight point 63. In other words, the operation of any one of these fingers will raise the weight point 63 precisely the same distance. But when the 120 finger 25 is actuated by a five cent piece the cumulative lever action will raise the weight point 63 higher than is possible by either a dime or five cent piece alone, with the result 125 that the hook 22 is lifted completely out of the lock slot 23 and the coin plate 20 permitted to move rearwardly without obstruction.

The same cumulative action occurs when a five cent piece is placed in each of the receivers 130 30, 31 and 32. The combined lifting action 130

of the fingers 26, 27 and 28 is enough to raise the locking hook 22 completely out of the slot 23, not necessarily as high as the combined action of the finger 25 in combination with one of the fingers 26, 27 and 28, but sufficiently high to completely clear the slot so that the coin plate 20 is free to be moved as before.

The distance between the axis of the pivot shaft 34 and the point of contact of the shoulder 43 of each of the fingers 26, 27 and 28, is such that when a five cent piece is advanced under the point the respective finger will be lifted three-eighths inch at the place of its contact with either lever 68 or 69. The places of contact of the levers 68 or 69 are denoted 71, 72 and 73. These levers are pivoted together at 74, and the pivot is directly over the finger 27. This is also true of the fulcrum 64. Spring wires 75 are looped around the various fingers 26, 27 and 28 and the adjoining levers 68 and 69 to keep the parts in contact, yet permit freedom of movement.

The remote ends of the levers 68 and 69 are movable in guides 78 which keep these levers in proper positions over the various lift fingers. Similarly, the free end of the bar 62 is movable in a guide 79. These guides are fixedly secured to the guide plate 38. The points of connection of the hangers 66 and 67 with the levers 68 and 69 are located two-thirds the distance between the pivot 74 and the points of contact 71 and 73 of the levers with the fingers 26 and 28. A three-eighths inch raise of the lift finger 28 (for example) will raise the hanger 67 and its pivot connections one-fourth inch. The fulcrum 64 is located midway of the hangers 66 and 67. When the hanger 67 is raised by means of the finger 28 the point of pivotal connection of the yoke 65 with the hanger 66 becomes the fulcrum for the yoke, and since the fulcrum 64 is located midway of the yoke it follows that the one-fourth inch raise of the hanger 67 will be diminished to a one-eighth inch raise of the fulcrum 64.

In true proportion the pivot or weight point 63 will be raised only one-sixteenth inch. The point of contact 70 instead of being the power point now becomes the fulcrum for the bar 62. Again, by a multiplication of the leverage, the tongue 60 will raise the contact screw 59 a sufficient distance to elevate the hook 22 one-eighth inch or one-third the distance requisite to release the coin plate 20. In other words, a five cent piece will contribute one-third of the elevation of the hook 22 necessary to unlock the mechanism. The remaining two-thirds is contributed by a ten cent piece in the manner already explained.

What has been said in connection with the lift finger 28 is true of each of the other lift fingers 26 and 27. The operation of any two of the five cent lift fingers will result in a two-thirds elevation of the locking hook 22, and the operation of all three of the five cent lift

70 fingers in unison will produce a three-thirds elevation of the locking hook or a complete displacement thereof from within range of the lock slot 23. To make this clear, a three-eighths raise of the lifter 27 will raise the pivot 74 (Fig. 3) three-eighths inch because the point of contact 72 is directly under this pivot. Since the hangers 66 and 67 are located at distances away from the pivot 74 equal to two-thirds of the distances between 72-71 and 72-73 it follows that the fulcrum 64 will be elevated only one-eighth inch.

75 By reverting to the foregoing description it will be found that the pivot or weight point 63 will be elevated one-sixteenth inch and the hook 22 one-eighth inch, the same as in the instance of the operation of the finger 28. The operation of the finger 26 will be the same as that of the finger 28, only the hanger 67 becomes the fulcrum for the yoke 65, whereas 80 in the first instance the hanger 66 acted as the fulcrum for the yoke.

85 The operation is readily understood. Assume that the sale price of the article desired to be purchased is fifteen cents. The coin control requires the insertion of coins having an aggregate value of fifteen cents before the locking hook 22 will be lifted sufficiently high out of the lock slot 23 to permit an unimpeded inward movement of the coin plate 20 and plunger 13. A full inward movement of the plunger is required before the article will be dispensed. The intending purchaser has a dime and a five cent piece. He must insert the dime in the dime hole 48 and the five cent 90 piece in one of the holes 49.

95 He cannot insert the five cent piece in the hole 48 because the latter is too small and should he insert the dime in one of the holes 49 he would lose his money as soon as the plunger 13 is pushed in far enough to bring the dime within range of the slug discharge opening 45. But it is assumed that the purchaser has inserted the coins in the proper holes. An inward push on the plunger will bring the dime under the shoulder 43 of the finger 25 (Fig. 4) and the five cent piece under the shoulder 43 of the finger 26 (Fig. 5). Both fingers will be raised. The shaft 34 constitutes the fulcrum, the shoulders 43 the power points and the places of contact 70 and 71 of the fingers 25 and 26 with the lever system the weight points, thus for the time being making the fingers 25 and 26 levers of the third order.

100 The combined and cumulative action of the fingers 25 and 26 is to produce a rocking of the bar 62 upon its fulcrum 64 and the lever 68 upon its pivot 74. The yoke 65 will yield, due to the connection of the lever 68 with one end thereof by means of the hanger 66 and the cumulative lever action is to raise the weight point 63 to such distance that the hook 22 will be elevated completely 110 out of the lock slot 23.

By this time the coins have reached the neighborhood of the webs 44. Thus far the coins have been prevented from dropping through. As soon as the hook 22 is elevated out of range of the front end of the slot 23 a continued push on the plunger and the coin plate 20 will effect full registration of the coin holes 48 and 49 with the coin slots 46 through which the coins will fall into the drawer 47. The hook 22 will now fall to its original position as will also the fingers 25 and 26. The push continues until the inner end of the slot 56 stops the forward lug 21. This represents the full inward movement of the plunger.

Upon the following forward movement of the plunger the article will be discharged from the column 4 into the chute 11 by the discharger slide 5. The rounded leading edge 57 of the forward lug 21 will displace the hook 22 so that the hook can drop back into its lock slot 23 and assume the position shown in Figure 1. As the forward ends of the receivers 29 to 32 pass under the shoulders 43 the various lift fingers are momentarily raised but immediately drop to their original positions by virtue of the pressure imposed upon the lock release 41 by the spring 40. The forward edges of the receivers are slightly bevelled at 76 (Figs. 4 and 5) so that they can readily pass under the shoulders.

Should the intending purchaser have three five cent pieces he may insert them in the holes 49. Upon now pushing in on the plunger there will be a concerted and cumulative action of the fingers 26, 27 and 28 which, being applied to the weight point 63 will elevate the hook 22 a distance requisite to unlock the coin plate 20. It is to be observed that the pivot 63 retains its identity as the weight point under all circumstances. Regardless of what set of levers is operated the duty of raising the lock release 41 is ultimately imposed upon the pivot 63 which thus becomes the weight point.

But the point of contact 70 of the master bar 62 with the finger 25 does not always retain the distinction of being the power point as in the instance when the finger 25 is solely actuated by a dime. The operation of any two or all three of the five cent fingers 26, 27 and 28 will convert the point 70 into the fulcrum of so much of the lever system as is then retained operative. Indeed, the point 70 does not retain its distinction as the sole power point even when a single five cent finger is operated in unison with the dime finger 25 for then the distinction is shared by any one of the contact points 71, 72 or 73, depending on which one of the five cent fingers is brought into play.

It therefore follows that even though the compound lever system remains in the second order the power and fulcrum points are quite free to shift with absolutely no interference

to the operation of the system. It only remains to say that the accurately formed slots 51 and 52 in the front plate 19 (Fig. 6) will exclude twisted and warped coins as well as abnormally thick slugs. Undersize slugs of proper thicknesses will not get into the machine far enough to work the vending mechanism for they will fall through the discharge openings 45. Coins intentionally or accidentally remaining stuck in the openings 48 and 49 will be ejected by the tongues 54 as the coin plate 20 completes its inward stroke.

Briefly reviewing the advantages of the coin control, it is an outstanding feature that the single coin control mechanism is the common actuator of a plurality of article columns 4, and that it requires only one manual operation to obtain the article after the coins are once inserted. The mechanism gauges the coins both for diameter and thickness, and as long as the intending purchaser has coins equal in value to that of the article he desires he will be certain to complete his purchase upon properly operating the machine.

Battered and sticking coins are forced out so that an operation of the machine cannot be repeated until a new set of coins is inserted. If coins of an insufficient amount are placed in the receivers such coins will be returned to the purchaser and will not drop out of reach in the machine. Such coins will not serve to unlock the machine, and it is only by the insertion of coins of sufficient value that this object can be accomplished. On the principle already announced, it is possible to devise a lever system which can be proportioned to operate by any desired combination of coins aggregating given values.

Although the lugs 21 are intended to be fixed to the plunger 13, the connection is not so inseparable that the coin control may not be replaced by a new one should it be necessary to do so. Regarding the lugs 21 as being of a separable nature it is readily seen that a material saving in express charges can be effected by merely returning the coin control to the factory should a repair become necessary, rather than the entire vending machine, which in practice can be made in some size.

While the construction and arrangement of the improved coin control is that of a generally preferred form, obviously modifications and changes may be made without departing from the spirit of the invention or the scope of the claims.

I claim:

1. A coin control comprising locking means capable of assuming locking and unlocking positions, a lever required to be swung a given distance for actuating the locking means, and means for contributing parts of the requisite motion, the total motion equalling the distance for operating the lever

to displace the locking means to the unlocking position.

2. A coin control comprising locking means capable of assuming locking and unlocking positions, a compound lever in connection with the locking means, and means gauged by an assemblage of coins and actuated thereby to cumulatively operate the compound lever for the displacement of the locking means into the unlocking position.

10 3. A coin control comprising locking means capable of assuming locking and unlocking positions, a plurality of means for operating the locking means, and a compound lever 15 cumulatively actuatable by said plurality of means at separated points along said compound lever to displace the locking means sufficiently to assume the locking position.

4. A coin control comprising locking means 20 capable of assuming locking and unlocking positions, a compound lever in connection with the locking means, and a set of lift fingers individually operable by coins and bearing upon the compound lever at separated 25 points to summarize the various operations of the lift fingers in a single operation of the compound lever to displace the locking means into the unlocking position.

5. A coin control comprising locking 30 means capable of assuming locking and unlocking positions, a set of coin-operated lift fingers the operation of each of which being fractional as regards the requisite movement of the locking means to assume the unlocking position, and a compound lever in 35 connection with said locking means upon which the fractional movements of said lift fingers are summarized to produce a movement of the compound lever to fully dis- 40 place the locking means into the unlocked position.

6. A coin control comprising locking means capable of assuming locking and unlocking positions, a set of lift fingers, a compound lever having common bearing on said 45 set of fingers and responding to a movement of any of the lift fingers, and movable means receiving coins for movement of the coins against a selected plurality of fingers to accumulate the compound lever with the accumulated movements of said selected fingers to displace said locking means into the unlocking position.

7. A coin control comprising locking 55 means capable of assuming locking and unlocking positions, actuator means in connection with the locking means, a set of lift fingers each being capable of fractionally moving the actuator means to displace the locking means toward the unlocking position, receiver means for receiving various coins of a determined aggregate value, and means for moving the receiver means to move said coins against a selected plurality of the 60 fingers to transmit the concerted movement of 65

said fingers to said actuator means for a movement of the locking means into the unlocking position.

8. A coin control comprising locking means capable of assuming locking and unlocking positions, a lock release with which said locking means has connection, a set of lift fingers individually operable by coins of selected denominations, and a compound lever traversing said fingers and converting the fractional movements of a selected plurality of the fingers into a single movement of said lock release to displace the locking means into the unlocking position.

70 9. A coin control comprising locking means capable of assuming locking and unlocking positions, actuator means susceptible of a progressive action to progressively displace said locking means toward the unlocking position, and means responsive to and gauging a heterogeneity of coins and applying fractional movements to said actuator means by which they are summarized into a single displacement of the locking means to the unlocking position.

75 10. A coin control comprising locking means capable of assuming locking and unlocking positions, a lock release with which the locking means has contact, a set of lift fingers, receiver means for moving a plurality of coins against companion lift fingers to produce fractional movements of each, and a leverage system with which said lift fingers have separated points of contact, said system including an equalizer bar in pivotal connection with the lock release and summarizing said fractional movements into a single movement of said pivotal connection to advance the locking means to the unlocking position.

80 11. A coin control comprising locking means capable of assuming locking and unlocking positions, a set of coin-operable fingers, a leverage system traversing the fingers comprising a pair of levers having a pivotal connection and bearing upon one of the fingers and having the remote ends bearing on adjoining fingers, a yoke having hangers connected with said levers, an equalizer bar bearing on another finger and fulcrumed to the yoke, and a lock release to which said bar is pivoted and with which the locking means has movable contact.

85 12. A coin control comprising locking means, a lock release with which the locking means has contact, a set of coin operable lift fingers, and a leverage system having components bearing upon the lift fingers at points of contact which variously become power and fulcrum points depending upon the operation of said fingers, said system including an equalizer bar having a pivotal connection with the lock release which always remains the weight point.

90 13. In a coin control, a fixed base plate hav-

ing a limiting slot, a plunger, and a coin plate
slidable over the base plate by operation of
the plunger having lugs by which connection
of the coin plate is made with the plunger,
one of said plugs occupying said slots to limit
the reciprocation of the plunger.

14. A coin control comprising locking
means, actuator means for displacing the
locking means from a locking to an unlocking
position, and means adjustable by an assort-
10 ment of coins to assume an ultimate adjust-
ment at which said actuator means will es-
tablish the locking means in the unlocking
position.

15. A coin control comprising locking
15 means, actuator means for displacing the
locking means, and means requiring the ap-
plication thereto of an optionally selected as-
sortment of coins for the operation of the ac-
tuator means to an extent requisite for the
20 displacement of the locking means to an un-
locking position.

16. A coin control comprising locking
means, actuator means for displacing the
locking means, and feeler means to touch a
25 plurality of coins thus to establish the extent
of movement of the actuator means in urging
the locking means toward an unlocking posi-
tion.

17. A coin control comprising locking
30 means, actuator means for displacing the
locking means, and feeler means to touch a
spread out assortment of coins thus to estab-
lish the extent of movement of the actuator
means in urging the locking means toward
35 an unlocking position.

18. A coin control comprising locking
means, actuator means for displacing the
locking means, and plural feeler means to si-
multaneously touch an assortment of coins
40 thus to establish the extent of movement of
the actuator means in urging the locking
means toward an unlocking position.
